COMBINED COLLAR HOLDER AND TIE CLASP

William J. Morse, Attleboro, Mass., assignor to
Morse Andrews Co., a corporation of Massachusetts

Application August 27, 1934, Serial No. 741,655

8 Claims. (Cl. 24—73)

My present invention relates to jewelry construction and has particular reference to tie ornaments. Ornamental effects have heretofore been obtained by inserting stick pins and the like in ties, the stick pins passing through the ties, or by using ornamental tie holders. The use of stick pins is injurious to the tie fabrics, and ornamental tie holders are only effective during the summer, as the vests worn during the other seasons conceal the tie holders. It is the principal object of my invention to provide an ornamentation for ties which does not injure the fabric in any way, and which is visible at all times.

Moreover, it has been found that ties should be spaced away from the shirt, particularly in the region of the tie knot, in order to present a more attractive appearance; the tie holders now in use tend to hold the tie adjacent the shirt, thus decreasing the attractive effect. It is a further object of my invention to provide a tie holder which will maintain the tie in proper relation to the shirt, and which will permit slight movements of the tie due to movements of the wearer.

With the above and other objects and other advantageous features in view, my invention consists of a novel arrangement of parts more specifically disclosed in the detailed description following, in conjunction with the accompanying drawing, and more particularly defined in the claims appended hereto.

In the drawing,

Fig. 1 is a diagrammatical view disclosing the appearance of the novel tie holder when in use;

Fig. 2 is a plan view thereof;

Fig. 3 is an end view thereof;

Fig. 4 is a perspective view of the novel tie clasp, the parts being in unlatched relation;

Fig. 5 is a plan view of the tie clasp, the parts being in latched position; and

Fig. 6 is a view similar to Fig. 2, but showing a modified construction.

I have found it desirable to provide ornamentation for a tie which is visible at all times, and particularly when a vest is worn, and to utilize the ornamentation as a means for maintaining the tie in proper spaced relation to the shirt. To this end, I provide a collar holder which functions as a base for supporting a tie ornament, this tie ornament consisting of a ring or similar tie-engaging element which may be fastened to the tie, preferably just below the knot, and which may carry any desired ornamentation, whereby the tie is suitably ornamented and is continually maintained at the proper distance from the shirt.

Preferred embodiments of my invention are illustrated in the accompanying drawing, in which Fig. 1 discloses the general appearance of the novel construction when in use.

A preferred arrangement includes a collar holder head 10, having a front bar 11 of any desired ornamentation or shape and a rear spring bar 12 which is secured to the forward bar by a connector 13, the rear spring bar having ends 14 and 15 provided with pressure lugs 16 and 17; the ends of the spring bar are shaped to guide the edges of a collar underneath the pressure lugs, which cooperate with the front bar to firmly grip the collar ends.

The connector 13 has an outwardly extending forward support 18 which may be formed integral with the connector, the support including a yoke 19 which is secured to the connector 13 and a forwardly extending rod element 20 which is rolled at its end to form an enlarged head 21. A tie clasp 22 is mounted on the rod element before the head 21 is formed, see Figs. 4 and 5, and has a rear portion 23, preferably made of sheet metal, which is stamped or cut so as to provide a curved seat 24 and a cooperating strap 24a spaced from the seat, the seat and strap forming a cylindrical bearing which is slidably locked on the rod 20.

The rear portion has a catch opening 25 at one end and is slotted at the other end to provide a hinge bar 26, for receiving a hinge connection 27 at one end of a front element 28, the front element having a hook 30 at its other end for releasable engagement with the catch opening 25.

The use of the improved tie clasp may now be explained: The collar holder portion is first attached on the collar, thus bringing the tie clasp in proper position adjacent the tie and just below the knot. The front element 28 is now swung open to permit the tie to be inserted between the front element and the rear portion and is then moved to lock the latch and catch members together around the tie. The tie clasp may slide slightly along the rod 20 to accommodate itself to the tie and the collar used by the wearer, and holds the tie properly in spaced relation to the shirt, while at the same time functioning as an ornament for the tie.

If desired, the front element 28 may be ornamented in any desired manner, or may have ornamental figures or designs or jewelry secured or attached thereto. The parts may be made of stamped metal or of wire, as preferred, or of any other suitable material, and the front element 28 which as illustrated is of flexible spring wire, may be made of other material, such as for

example, chain stock, one end of the chain being locked to the hinge bar 29 or its equivalent and the other end of the chain being releasably engageable with the catch opening 25 or its equivalent.

Instead of using a rigid connection member 18, it may be desired for certain uses to have a more flexible connection; a specific construction is illustrated in Fig. 6, in which the collar holder and the tie clasp are secured together by a spring wire 31, which as shown is gripped firmly by lock member 32 of the collar holder connector 33, and passes through the opening formed between the strap 24 and the back of the rear portion 23. This construction permits a free movement of the tie clasp with respect to the collar holder without however permitting a separation of the two parts.

If desired, the tie clasp 23, which supports an ornament of a desired shape or form, may be used by itself; when so used it may consist of a back and a front which are hinged together, the free ends being detachably engageable, or it may consist of an arcuate spring member having two detachably engageable ends.

The above described constructions are readily adaptable for ornamenting bow ties, as the rod or the spring wire may be bent adjacent the tie clasp end to position the tie clasp in a generally vertical relation to the collar holder. Or, the rod and wire may be replaced by a chain connection; the rod modification is preferred, however, as the tie clasp holds the bow tie in proper position besides functioning as an ornament.

While I have described a specific embodiment of my invention, it is obvious that desired changes in materials used, in the formation of the parts, in their relative positioning, and in their individual functions, may be made to suit the requirements of different designers, within the spirit and the scope of the invention as defined in the appended claims.

I claim:

1. In combination, a collar holder having a front member and a rear member, the contiguous ends of said members being adapted to releasably grip the tabs of a collar, a support element secured to said collar holder intermediate said ends, and a tie clasp secured to said support element.

2. In combination, a collar holder having a front member and a rear member, the contiguous

ends of said members being adapted to releasably grip the tabs of a collar, a support element secured to said collar holder intermediate said ends, and a tie clasp movably secured to said support element.

3. In combination, a collar holder having a front member and a rear member, the contiguous ends of said members being adapted to releasably grip the tabs of a collar, a support element secured to said collar holder intermediate said ends, and a tie clasp slidably secured to said support element.

4. In combination, a collar holder having a front member and a rear member, a connector for locking said members together at their center portions, the contiguous ends of said members being adapted to releasably grip the tabs of a collar, a support element secured to said connector, and a tie clasp secured to said support element.

5. In combination, a collar holder having a front member and a rear member, a connector for locking said members together at their center portions, the contiguous ends of said members being adapted to releasably grip the tabs of a collar, a support element secured to said connector, and a tie clasp movably secured to said support element.

6. In combination, a collar holder having a front member and a rear member, a connector for locking said members together at their center portions, the contiguous ends of said members being adapted to releasably grip the tabs of a collar, a support element secured to said connector, and a tie clasp slidably secured to said support element.

7. In combination, a collar holder having a front member and a rear member, the contiguous ends of said members being adapted to releasably grip the tabs of a collar, a flexible support element secured to said collar holder intermediate said ends, and a tie clasp secured to said support element.

8. In combination, a collar holder having a front member and a rear member, the contiguous ends of said members being adapted to releasably grip the tabs of a collar, a flexible support element secured to said collar holder intermediate said ends, and a tie clasp movably secured to said support element.

WILLIAM J. MORSE. 50
